GAS BURNER

Filed Jan. 7, 1931

UNITED STATES PATENT OFFICE

BENJAMIN C. BARTLEBAUGH, OF WHEELING, WEST VIRGINIA

GAS BURNER

Application filed January 7, 1931. Serial No. 507,260.

The invention relates to a new and improved gas burner designed primarily for use with the "burn-over" gas heater of my U. S. application Serial No. 507,259, filed January 7, 1931, although said burner is not restricted to this particular field of use.

It is the object of the invention to provide an exceptionally simple and inexpensive burner construction, yet one which will be highly efficient, will operate to equal advantage in the consumption of natural or artificial gas, and will function properly without allowing escape of gas whether the gas pressure be low or high.

With the foregoing in view, the invention resides in the novel subject matter herein-after described and claimed, description being accomplished by reference to the accompanying drawing.

Fig. 1 is a transverse sectional view through a gas heater showing the burner installed.

Fig. 2 is a perspective view of the burner.

Fig. 3 is a vertical longitudinal section partly in elevation, as indicated by line 3-3 of Fig. 1.

A construction is disclosed which has proven to be of great advantage from all standpoints, and while such construction will be herein specifically explained, it is to be understood that minor variations may be made.

The burner embodies a horizontally elongated shell 5 preferably of quarter-cylindrical form, the curved upper portion of said shell being provided with gas discharge perforations 6 and 7, while the bottom of said shell is formed with two longitudinally spaced openings 8. The upper ends of two vertical pipe nipples 9 pass through the openings 8 and are threaded into two T's 10 within the shell 5, said T's opening toward opposite ends of said shell and constituting gas distributing heads. Nuts 11 are threaded upon the nipples 9 and coact with the lower ends of the T's 10 in securely fastening said nipples in the openings 8. Threaded upon the lower ends of the nipples 9, are two vertically disposed air and gas mixers 12 whose lower ends are provided with elbows 13. The upper ends of these elbows embody nozzles 14

for vertically discharging gas, and the lower ends of said elbows are directed horizontally inward toward each other. Two horizontal pipe nipples 15 are threaded into the lower ends of the elbows 13 and are disposed in axial alignment with each other, the inner ends of these nipples 15 being threaded into the head 16 of a T 16. The shank of the T is disposed upwardly, and the reduced down-turned end of a service L 17, is threaded into said shank. A horizontal gas pipe 18, transverse to the nipples 15, is threaded into the service L 17.

The construction described, provides such a tortuous course for the incoming gas, that its velocity is checked when said gas is at unusually high pressure. Thus, the gas is prevented from blowing from the perforations 6 and 7 with such force as to prevent proper combustion. Then too, when the gas is at unusually low pressure, for instance, the pressure of natural gas during cold weather, none of this gas can escape unburned, due to the vertical positions of the mixers 12. The natural tendency of the gas to ascend as it leaves the nozzles 14, prevents it from escaping through the air intake openings of the mixers 12, whereas if these mixers were horizontally positioned, some of the gas would escape through said openings. A further advantage of the improved construction, is that it operates to equal advantage with either artificial or natural gas, whereas prior burners have necessitated special details for burning natural gas and other special details for the combustion of artificial gas. Whether the gas be natural or artificial, the improved burner operates at a much higher state of efficiency than any other burner with which I am familiar.

Attention is invited to the fact that the burner is of quarter-cylindrical form. If it were a complete cylinder, it would be so large that in burning or trying to burn a small amount of gas for heating a small room, proper combustion could not be produced, for the quantity of gas fed into the burner would be too small with regard to the quantity of air contained in said burner. The shape of the burner provides it with a large face over which to distribute and burn the gas in single

jets of flame. This face of the burner presents as much area for burning gas as there would be in a conventional five inch cylindrical burner, so that large consumption of gas for heating large rooms can be readily effected, regardless of the fact that the burner is sufficiently small to consume small quantities of gas for heating small rooms. Another advantage of the shape of the burner is that, if it were cylindrical, it could not be placed as tight against the fire wall in the heater as if it were not of cylindrical form.

I claim:—

18. 1. A gas burner comprising a horizontally elongated shell provided with a perforated upper portion, said shell having two longitudinally spaced openings in its bottom, two vertical pipe nipples passing through and secured in said openings respectively, gas distributing heads on said nipples within said shell and opening toward opposite ends of the latter, two vertical gas and air mixers connected with the lower ends of said nipples respectively, the lower ends of said mixers being provided with elbows whose lower ends project inwardly toward each other, two horizontal pipe nipples connected with said lower ends of said elbows and projecting inwardly toward each other, a **T** with whose head the 20 inner ends of said horizontal nipples are connected, the shank of said **T** being disposed vertically, a service **L** connected with said shank of said **T**, and a horizontal gas pipe connected with said service **L**.
25. 2. A gas burner comprising a horizontally elongated shell provided with a perforated upper portion, said shell having two longitudinally spaced openings in its bottom, two vertical pipe nipples passing through and secured in said openings respectively, gas distributing heads on said nipples within said shell and opening toward opposite ends of the latter, two vertical gas and air mixers connected with the lower ends of said nipples 30 respectively, the lower ends of said mixers being provided with elbows whose lower ends project inwardly toward each other, two horizontal pipe nipples connected with said lower ends of said elbows and projecting inwardly toward each other, a **T** with whose head the inner ends of said horizontal nipples are connected, the shank of said **T** being disposed vertically, a service **L** connected with said shank of said **T**, and a horizontal gas pipe connected with said service **L**.
35. 3. A gas burner comprising a horizontally elongated shell provided with a perforated upper portion, said shell having two longitudinally spaced openings in its bottom, two vertical pipe nipples passing through and secured in said openings respectively, gas distributing heads on said nipples within said shell and opening toward opposite ends of the latter, two vertical gas and air mixers connected with the lower ends of said nipples 40 respectively, the lower ends of said mixers being provided with elbows whose lower ends project inwardly toward each other, two horizontal pipe nipples connected with said lower ends of said elbows and projecting inwardly toward each other, a **T** with whose head the inner ends of said horizontal nipples are connected, the shank of said **T** being disposed vertically, a service **L** connected with said shank of said **T**, and a horizontal gas pipe connected with said service **L**.
45. 4. A gas burner comprising a horizontally elongated shell provided with a perforated upper portion, said shell having two longitudinally spaced openings in its bottom, two vertical pipe nipples passing through and secured in said openings respectively, gas distributing heads on said nipples within said shell and opening toward opposite ends of the latter, two vertical gas and air mixers connected with the lower ends of said nipples 50 respectively, the lower ends of said mixers being provided with elbows whose lower ends project inwardly toward each other, two horizontal pipe nipples connected with said lower ends of said elbows and projecting inwardly toward each other, a **T** with whose head the inner ends of said horizontal nipples are connected, the shank of said **T** being disposed vertically, a service **L** connected with said shank of said **T**, and a horizontal gas pipe connected with said service **L**.
55. 5. A gas burner comprising a horizontally elongated shell provided with a perforated upper portion, said shell having two longitudinally spaced openings in its bottom, two vertical pipe nipples passing through and secured in said openings respectively, gas distributing heads on said nipples within said shell and opening toward opposite ends of the latter, two vertical gas and air mixers connected with the lower ends of said nipples respectively, the lower ends of said mixers being provided with elbows whose lower ends project inwardly toward each other, two horizontal pipe nipples connected with said lower ends of said elbows and projecting inwardly toward each other, a **T** with whose head the inner ends of said horizontal nipples are connected, the shank of said **T** being disposed vertically, a service **L** connected with said shank of said **T**, and a horizontal gas pipe connected with said service **L**.

In testimony whereof I affix my signature.
BENJAMIN C. BARTLEBAUGH.
